FURNACE REGENERATOR

Ernest E. Lail, Athol Springs, N. Y.

Application August 30, 1952, Serial No. 307,187

9 Claims. (Cl. 263—51)

This invention relates generally to furnaces of the reversing or regenerative type, and more particularly to an improved checker or regenerator arrangement for such furnaces.

The checker arrangements now commonly used for purposes of regeneration possess certain severe disadvantages since they utilize vertically extending ducts or passages through the checkers. It is extremely difficult to clean such checker passages because of the roof directly over the checker which prevents the workers from seeing what they are doing. As a result, it is virtually impossible to properly clean such checkers, and even with almost continuous effort after about one hundred heats at least half of the checker area is plugged so tightly that air and gases cannot pass therethrough, and after about one hundred and fifty heats almost nine-tenths of the checker area is no longer useable. Under these conditions, regeneration is at a very low point and is extremely inefficient, and the pull of the furnace stack is insufficient to take away the furnace exhaust, resulting in damage to the furnace lining and end wall, and to other points. In addition, the time required for the heats becomes excessive, and fuel consumption increases for each ton of steel produced in the furnace. Also, because of the consequent variation in the amount and temperature of air passing through the vertical checker, it is virtually impossible to devise an automatic control that will feed air to the furnace under constant conditions from start to finish of a particular campaign.

While some attempts have been made to overcome these deficiencies and disadvantages by utilizing a horizontal checker arrangement, such prior art efforts have not completely solved the aforesaid problems. For example, in one prior art arrangement, the checkers are arranged in vertically superposed layers and infiltration tends to result by reason of exposure to cold walls between the checker layers, and by reason of the fact that the sides of the checkers abut cold walls. Furthermore, the use of vertically superposed layers to produce greater checker length requires more room than usual below ground level. In addition, the upper checker layer is excessively heated compared to the lower layers, whereby the checker area is not evenly heated throughout, and means must be provided for protecting such upper layer. For these and other reasons, such a prior art arrangement is of relatively low efficiency, requires relatively frequent cleaning, and otherwise fails to completely satisfactorily solve the aforesaid problems.

Accordingly, it is an object of this invention to provide a furnace checker arrangement wherein the checker passages can be readily cleaned and kept clean with a minimum of expense and effort and a maximum of efficiency.

In addition, it is an object of this invention to provide a regenerator or checker arrangement wherein different parts of the checker area can be cleaned at different times, rotating the parts being cleaned whereby to provide a specific time interval between cleanings of the same part,

2

thus maintaining even regeneration throughout the entire campaign of the furnace.

A further object of this invention is to provide a reversing furnace checker arrangement which can readily be cleaned, and wherein regeneration is maintained at a satisfactory level even if a portion of the checker area should become clogged for a period of time.

It is also an object of this invention to provide a furnace regenerator wherein the regenerator is heated evenly throughout its entire area, thus avoiding undue heating of any one part thereof.

Another object of this invention is to provide a furnace regenerator wherein exposure of the heated air or air to be heated to cold walls is reduced to a minimum, whereby to prevent any damage or decreased efficiency by reason of infiltration.

It is also an object of this invention to provide a furnace checker arrangement which does not require an undue or unusual amount of space in any direction.

20 A further object of this invention is to provide a relatively simple furnace checker arrangement which does not require many of the complex items now thought necessary in conventional checker installations, simplifying the sewers, reducing the number of valves, discarding air fans, and the like.

The foregoing and other objects will become immediately apparent upon reading the ensuing detailed description, taken together with the accompanying drawings forming a part thereof and wherein:

30 Fig. 1 is a side view in vertical section through my improved furnace checker arrangement, showing the furnace uptake and the stack, and taken about on line I—I of Fig. 2;

35 Fig. 2 is a top view in horizontal section taken about on line II—II of Fig. 1; and

Fig. 3 is a front view in vertical section taken about on line III—III of Fig. 1.

Referring now to the drawings, my improved checker arrangement is shown in Fig. 1 at one end of a conventional reversing furnace, it being understood that a duplicate checker arrangement will be found at the other end of the furnace. The furnace, which is of any conventional construction, is generally designated 1, and includes a slag pocket 2 and an uptake 3, the slag pocket terminating at its outer end in an inclined surface 4 and a bridge wall 5. If desired, there may be provided an air cooled passageway 6 to permit cooling and protecting of the bridge wall. Bridge wall 5 serves to define the lower part of the usual fantail arch, and the furnace is provided with appropriate conventional supporting and reinforcing structures the details of which need not be set forth herein since they are well known and form no part of my invention.

55 The checker or regenerator is generally designated 7, and is enclosed by a top wall 8 and side walls 9, 10, and 11. Checker 7 is of the single surface type, wherein the heat of the outgoing or off gases is applied to and absorbed by the checker, and is given back to the incoming cold air from the same surfaces of the checker which received the heat. According to my invention, checker 7 is divided into two sections or passes 12 and 13, arranged in spaced apart side-by-side relation, each formed in a conventional manner of known checker brick material the details of which form no part of this invention, and each provided with multiple substantially horizontal ducts 14 extending therethrough towards side walls 9 and 11 and substantially parallel to side wall 10. A wall 15 extends across the front end of passes 12 and 13, and said checker passes are spaced from the fantail arch and bridge wall 5 whereby to provide a vertically extending passage 16 therebetween, which passage terminates at its lower end in a soot pocket or

60 65 70

sewer 17 receiving soot carried by the off gases before they pass through the checker. Of course, the checkers are supported by a suitable foundation, as at 18, whereby they are spaced above sewer 17.

Passes 12 and 13 of checker 7 are spaced apart, with their adjacent side walls 19 and 20 defining a passage 21 therebetween, and wall 15 is broken away to permit communication between passage 21 and the furnace. Also, the remote side walls 22 and 23 of said passes are spaced from walls 9 and 11, respectively, to provide passages 24 and 25 therebetween, each of said passages being closed at its inner end by wall 15.

Walls 19, 20, 22 and 23 are inclined or extended inwardly, whereby passages 21, 24 and 25 taper in width from a maximum at their open ends to a minimum at their closed ends, and from a maximum at their lower portions to a minimum at their upper portions, all as clearly shown in Figs. 2 and 3. The passage area at any point corresponds to the total checker duct area beyond that point, or the variation in passage area between any two points corresponds to the total duct area between such points, which arrangement insures an even distribution of off gases and of incoming air throughout the checker area. Also, the inward and upward taper of the passages compensates for the tendency of hot gases to rise.

Passages 21, 24 and 25 terminate at their lower ends in soot sewers 21', 26 and 27, respectively, and sewers 26 and 27 communicate at one end with a cross passage and sewer 28 which in turn communicates with a conventional stack 29.

Thus, as indicated by broken line arrows in Fig. 2, the hot exhaust or off gases pass from uptake 3 through passage 21 and ducts 14 of each section or pass of checker 7, heating the duct wall surfaces of said checker sections, and then through passages 24 and 25 to passage 28 and stack 29. Incoming air follows the same path but in a reverse direction, as indicated by solid line arrows in Fig. 2, being heated by such duct wall surfaces.

In order to facilitate cleaning of ducts 14, walls 9 and 11 are provided with multiple clean-out openings 30 therein, which openings are aligned with said ducts 14. At their outer ends, openings 30 are closed by any appropriate removable plug or cap means 31. Thus, when it is desired to clean the checker ducts, the caps 31 are removed and a cleaning tool can be inserted through openings 30 and ducts 14 to scrape or otherwise clean the interior of said ducts, the dirt accumulations falling from the ducts into the sewers. Alternatively, compressed air can be used to clean the ducts, this arrangement being facilitated by the alignment of openings 30 and ducts 14. Of course, since openings 30 are in side walls 9 and 11, workers are readily able to see exactly what they are doing. Further, with the arrangement of ducts, openings and caps as disclosed, it is apparent that the ducts can be selectively cleaned, whereby for example one section of the checker area can be cleaned first, and then the other section, whereby regeneration is not substantially interrupted but is maintained at a satisfactory efficiency. Also, should certain of the ducts become clogged, there will still be a sufficient unclogged checker area to insure proper and efficient regeneration.

Furthermore, appropriate doors 32 and 33 are provided at opposite ends of sewers 28 and 17, respectively, whereby compressed air can be blown through said sewers to clear the same of soot and other accumulations therein. Similarly, the closed ends of sewers 26, 27 and 21' are provided with doors 34, 35, and 36, respectively, and a capped opening 37 is provided at the lower part of wall 10, whereby compressed air can be blown through all of these sewers and passages to clear the same of soot and dirt accumulations. In this way, with a minimum number of doors operable in any desired known manner, the sewers and passages can be readily cleaned and maintained clear at all times.

In addition, passage 21 is divided by a wall 38 extending from top to bottom thereof. Wall 38 serves as a

baffle dividing the off gases and deflecting them through the two passes, thereby increasing the regeneration, and protecting one pass or section while the other is being cleaned, as well as a support for the center arch of the top wall or roof 8.

Thus, it is readily apparent that the instant invention fully accomplishes its aforesaid objects. A practical, space-saving horizontal checker arrangement is provided wherein even distribution of heat throughout the checker area is insured, infiltration is kept at a minimum, regeneration is maintained at a high efficiency, and wherein in the checker ducts, together with the various sewers, may be readily cleaned and kept clean.

While a preferred embodiment of my invention is disclosed in detail herein, it is obvious that my invention is not necessarily limited to the particular details of such embodiment, but that they may be modified without departing from the scope of the invention. Accordingly, I intend that my invention be limited solely by the scope of the appended claims. Also, in defining the arrangement of regenerator sections in the appended claims, it will be appreciated that the term "parallel" is used in its electrical sense as distinguished from its geometrical meaning.

Having completely disclosed and fully described my invention in a preferred embodiment thereof, what I claim as new is as follows:

1. In combination with a reversing furnace, regenerators therefor connected to each end thereof, each of said regenerators comprising a pair of sections arranged in parallel in side-by-side relation and spaced apart to provide a passage therebetween communicating with said furnace, and multiple substantially horizontal ducts extending in generally opposite directions through each of said sections from said passage to receive and provide a path first for off gases from said furnace and then for air passing to said furnace when said furnace is reversed.

2. A reversing furnace regenerator comprising, a pair of regenerator sections arranged in parallel and spaced apart in side-by-side relation to provide a first passage therebetween extending longitudinally thereof, means defining second passages on opposite sides of said sections, said first passage being of a inwardly tapered formation from the end thereof adjacent the furnace to the opposite end thereof and from the bottom to the top thereof, whereby to provide an even distribution of off gases to said sections, and multiple ducts extending substantially horizontally in generally opposite directions through each of said sections between said first passage and said second passages, said ducts receiving and providing a path first for off gases from the furnace and then for air passing to the furnace when the furnace is reversed.

3. A reversing furnace regenerator comprising, a pair of regenerator sections arranged in parallel in spaced apart side-by-side relation to define a first passage between adjacent sides thereof, walls spaced from the remote sides of said sections to define second passages between said walls and said sections, multiple substantially horizontal ducts in each of said sections extending in generally opposite directions between said first and second passages, said ducts receiving and providing a path first for off gases from the furnace and then for air passing to the furnace when the furnace is reversed, means defining multiple clean-out openings in said walls aligned with said ducts, removable closures for said openings, and a soot baffle wall extending lengthwise of said first passage in spaced relation with said sections.

4. A reversing furnace regenerator comprising, a pair of regenerator sections arranged in parallel in spaced apart side-by-side relation to define a first passage between adjacent sides thereof, walls spaced from the remote sides of said sections to define second passages between said walls and said sections, multiple substantially horizontal ducts in each of said sections extending in generally opposite directions between said first and second

passages, said ducts receiving and providing a path first for off gases from the furnace and then for air passing to the furnace when the furnace is reversed, means defining multiple clean-out openings in said walls aligned with said ducts, and removable closures for said openings.

5. A reversing furnace regenerator comprising, a pair of regenerator sections arranged in parallel and spaced apart in side-by-side relation with their adjacent sides defining a first passage therebetween, means closing said first passage at one end thereof, walls spaced from the remote sides of said sections to define therewith second passages between said walls and said sections, means closing said second passages at the end thereof remote from the closed end of said first passage, each of said first and second passages tapering inwardly from the open end to the closed end thereof and from the bottom to the top thereof, whereby to evenly distribute off gases and air to said sections, and multiple substantially horizontal ducts extending in generally opposite directions through each of said sections between said first passage and said second passages for receiving and providing a path first for off gases from the furnace and then for air passing to the furnace when it is reversed.

6. A reversing furnace regenerator comprising, dual regenerator sections arranged in parallel in spaced apart side-by-side relation with their adjacent sides defining a first passage therebetween, means closing said first passage at one end thereof, walls spaced from the remote sides of said sections to define therewith second passages between said walls and said sections, means closing said second passages at the end thereof remote from the closed end of said first passage, each of said first and second passages tapering inwardly from the open end to the closed end thereof and from the bottom to the top thereof, and multiple substantially horizontal ducts extending in generally opposite directions through each of said sections between said first passage and said second passages for receiving and providing a path first for off gases from the furnace and then for air passing to the furnace when it is reversed, the degree of taper of each of said passages being such as to cause a variation in passage area between any two points spaced therealong substantially corresponding to the total duct area between said points, whereby to evenly distribute off gases and air to said sections.

7. In combination with a reversing furnace, a regenerator therefor at one end thereof comprising, a pair of regenerator sections arranged in parallel in spaced apart side-by-side relation to define a first passage between adjacent sides thereof, walls spaced from the remote sides of said sections to define therewith second passages between said walls and said sections, multiple substantially horizontal ducts extending in generally opposite directions through each of said sections between said first and second passages for receiving and providing a path first for off gases passing from the furnace and then for air passing to the furnace when it is reversed, said first and second passages terminating at their lower ends in corresponding first and second sewers in open communica-

tion therewith, a first cross sewer at the end of said sections remote from said furnace communicating with said second sewers and with an exhaust passage, a removable closure between said first sewer and said first cross sewer, a second cross sewer at the end of said sections adjacent said furnace communicating with said first passage, removable closures between said second sewers and said second cross sewer, and removable closures at opposite ends of said first and second cross sewers.

- 10 8. A reversing furnace regenerator comprising, a pair of regenerator sections arranged in parallel in spaced apart side-by-side relation whereby their adjacent side walls define a first passage therebetween, wall means spaced from the remote side walls of said sections to define therewith second passages between said wall means and said remote side walls, multiple substantially horizontal ducts in each of said sections extending in generally opposite directions between said first and second passages for receiving and providing a path first for off gases from the furnace and then for air passing to the furnace when it is reversed, means defining clean-out openings in said wall means aligned with said ducts, removable closures for said openings, and a soot baffle wall extending lengthwise of said first passage in spaced relation with said adjacent side walls, said adjacent side walls converging inwardly and upwardly along their vertical extent and inwardly toward one end thereof along their lengthwise extent, and said remote side walls diverging upwardly along their vertical extent and toward the end thereof remote from said one end of said adjacent side walls along their lengthwise extent.
- 15 9. A reversing furnace regenerator comprising, a pair of regenerator sections arranged in parallel in spaced apart side-by-side relation to define a first passage between adjacent sides thereof, walls spaced from the remote sides of said sections to define second passages between said walls and said remote sides, said first passage tapering inwardly from one end thereof to the other and each of said second passages tapering inwardly from the end thereof adjacent said other end of said first passage to the opposite end thereof, and multiple substantially horizontal ducts extending in generally opposite directions through said sections from said first passage to said second passages, said ducts receiving and providing a path first for off gases passing from an associated furnace and then for air passing to the furnace when it is reversed.
